CLAIM

The ornamental design for an inhaler, as shown and described.

DESCRIPTION

FIG. 1 is a perspective view of an inhaler, showing our new design;

FIG. 2 is a perspective view of the inhaler, with the cover installed;

FIG. 3 is a side view of the inhaler of FIG. 2, with the inhaler rotated counterclockwise about 45°;

FIG. 4 is a side view as in FIG. 3, rotated a further 90°;

FIG. 5 is a side view of the inhaler of FIG. 1, with the inhaler rotated counterclockwise about 45°;

FIG. 6 is a top view of the inhaler, with the cover installed; and,

FIG. 7 is a bottom view of the inhaler.

The broken line showing of the dosage indicator in FIGS. 1, 2, 3 and 5 is for illustrative purposes only and forms no part of the claimed design.

FIG. 2

FIG. 1

FIG. 4

FIG. 3

FIG. 7

FIG. 6
